UNITED STATES PATENT OFFICE.

ALEXANDER NIEDRINGHAUS, OF ST. LOUIS, MISSOURI.

BOAT.

933,331.

Specification of Letters Patent. Patented Sept. 7, 1909.

Application filed June 8, 1908. Serial No. 437,336.

To all whom it may concern:

Be it known that I, ALEXANDER NIEDRINGHAUS, a citizen of the United States, residing at St. Louis, Missouri, have invented a certain new and useful Improvement in Boats, of which the following is a full, clear, and exact description, such as will enable others skilled in the art to which it appertains to make and use the same, reference being had to the accompanying drawings, forming part of this specification, in which—

Figure 1 is a side elevational view partly in vertical section of a boat constructed in accordance with my invention; and Fig. 2 is a top plan view of a raft made up of a number of my improved boats.

This invention relates to a new and useful boat for transporting goods and merchandise.

20 The main object of my invention is to provide means for reducing the cost of handling and transporting goods and merchandise by water.

Another object of my invention is to provide a boat that is particularly adapted for transporting goods and merchandise on rivers or bodies of water that are comparatively shallow and which are filled with sand-bars. And still another object of my invention is to provide a boat that can be loaded on land, then placed in the water and towed to its destination, and thereafter lifted out of the water and turned into a certain position so that its contents will be discharged, thereby eliminating the operation of carrying the cargo from the shore to the boat and from the boat to the shore and consequently reducing the cost of handling and transporting freight by water.

40 Other objects and desirable features of my invention will be hereinafter pointed out.

To accomplish the objects above referred to I have devised a boat which consists of a closed tubular-shaped shell or casing constructed in such a manner that goods or merchandise can be placed inside of same and being of such dimensions that it can be loaded on the land, then placed in the water, and lifted out of the water and turned into a certain position to discharge its cargo. A device is located adjacent one end of the shell to which a tow-line or cable can be connected, and said device and a similar device at the other end of the shell, can be utilized to attach the shell to an apparatus

that lowers the shell into the water and lifts it out of the water.

As previously stated, my improved boat is adapted to be towed instead of propelled by means carried by the boat, and as the boat is comparatively small I prefer to arrange a number of the boats together to form a raft and then attach the raft to a boat provided with propelling mechanism.

In the preferred form of my invention as herein shown, the shell or casing in which the cargo is placed is arranged inside of one or more air-tight compartments that impart buoyancy to the shell and also protect the shell from snags or objects that are floating in the water.

Referring to the drawings which illustrate the preferred form of my invention, 1 designates a closed tubular shell, preferably of cylindrical-shape in cross section, and provided with conical-shaped ends 2 and 3. The forward or bow end 2 of the shell has an eye 4 or other suitable device connected thereto to which a cable or rope can be attached, and the rear or stern end 3 of the shell is also provided with an eye 5 to which a rope or cable can be connected so as to enable the shell to be hooked onto a lifting apparatus that lowers it into the water or lifts it out of the water. In the construction herein shown the eye 5 is connected to a cover 6 that closes an opening through which the cargo is placed in the shell and discharged therefrom, and this cover 6 is preferably so constructed that a water-tight joint is formed between the cover and the shell, said cover consisting of a screw-threaded plug that is screwed into a sleeve 7 on the stern end 3 of the shell. A flange 6^a on the plug 6 clamps a gasket 8 against an outwardly projecting flange 7^a on the sleeve 7, and the inner end of said plug clamps a gasket 9 or piece of packing against an inwardly projecting flange 7^b on the sleeve 7, as shown in Fig. 1. The particular type of cover that is used is immaterial so far as my broad idea is concerned and I do not wish it to be understood that my invention is limited to the construction herein shown. If desired, the shell can be provided on its upper side with an auxiliary opening that is closed by a cover 10 of similar construction to the cover 6, said cover 10 being screwed into a sleeve 11 that surrounds said auxiliary opening.

After the shell has been filled with the

goods that are to be transported, the cover, or covers, are screwed into place and the shell is then lowered into the water. A number of the boats can be arranged abreast 5 of one another, as shown in full lines in Fig. 2, so as to form a raft, each boat being connected by a short cable or rope 12 to a tow-line 13 that is attached to a boat provided with propelling mechanism. Instead of arranging the boats abreast of one another, as 10 above described, they can be arranged in tandem, as shown in dotted lines in Fig. 2, or in fact, in any other formation, and if desired, the boats can be lashed together by 15 ropes or cables that are connected to the eyes 4 and 5 at the opposite ends of the shells.

When the boats arrive at their destination they are lifted out of the water and 20 then arranged in a vertical position so that the exit 22 which each shell contains will pass out of the opening that the cover 6 closes.

From the foregoing it will be seen that I 25 have devised a boat that can be built at a low cost and which eliminates carrying the cargo from the shore to the boat and from the boat to the shore, thereby reducing greatly the cost of transporting freight by 30 water. Any goods or merchandise of small enough dimensions to pass through the openings that the covers 6 and 10 close can be transported in a boat of this construction, but the boat is particularly adapted for carrying grain, coal, ore, etc. that can be shoveled into the shell and which will discharge 35 quickly when the shell is arranged in an upright position. As the boat draws very little water it can be used advantageously on 40 rivers or bodies of water that are shallow and filled with sand-bars, such, for example as the Missouri River, and other streams that have no well-defined channel, and if the boats are connected together as a raft, 45 and the raft should strike a sand-bar it can be broken up easily and the separate boats freed by merely rolling them over and over or pulling them off into deeper water.

To impart buoyancy to the shell 1 and 50 enable the boat to carry heavy loads I prefer to arrange the shell inside of one or more air-tight compartments, said air-tight compartments also acting to protect the shell and prevent it from becoming crushed or 55 punctured by snags or objects floating in the water.

In the preferred form of my invention as herein shown the shell 1 is surrounded by a number of water-tight hollow ring-shaped 60 members 14, and said members are surrounded by a number of water-tight hollow ring-shaped members 15 that are staggered relatively to the ring-shaped members 14 so as to produce a strong and rigid structure. 65 The ring-shaped air compartments that sur-

round the conical-shaped ends of the shell conform to the shape of said ends so that the boat resembles a long cylinder provided with approximately conical-shaped ends. The hollow ring-shaped members which 70 surround the shell are confined in position by the flange 7^a on the sleeve 7 at the stern end of the shell, and a plate 16 at the bow end of the shell which carries the eye 4 to which the tow-line 12 is connected, said plate being connected to the shell by a fastening device 17.

The auxiliary cover 10 lies approximately flush with the exterior of the boat and if desired, said cover can be provided with a 80 socket 10^a for receiving a tool to unscrew said cover from the sleeve 11. I also prefer to provide the boat with a keel 18 that is of sufficient weight to prevent the boat from rolling so as to keep the auxiliary cover 10 85 out of the water. The shell 1 and the air compartments inside of which said shell is arranged can be made of any suitable material but I prefer to form them of sheet metal 90 on account of the low cost of manufacture and the strength which such material possesses.

Having thus described my invention, what I claim as new and desire to secure by Letters Patent is:

1. A boat for the purpose described, comprising a shell adapted to be filled on land, then placed in the water and towed to its destination, and thereafter lifted out of the water and turned out of its normal position to discharge its lading, a cover closing an opening in one end of said shell, and devices connected to said cover and to the opposite end of the shell to which tow lines or lifting cables can be attached.

2. A boat for the purpose described, comprising a closed shell that is adapted to be filled on land, then placed in the water and towed to its destination, and thereafter lifted out of the water and turned in an approximately upright position to discharge its cargo, said shell being provided at one end with an opening that is closed by a cover, and an air-tight compartment surrounding said shell; substantially as described.

3. A boat for the purpose described comprising a closed shell that is adapted to be filled on land, then placed in the water and towed to its destination, and thereafter lifted out of the water and turned in an approximately upright position to discharge its cargo, said shell being provided at one end with an opening that is closed by a cover, and a plurality of hollow members surrounding said shell to form air compartments; substantially as described.

4. A boat for the purpose described, comprising a closed shell that is adapted to be filled on land, then placed in the water and towed to its destination, and thereafter lifted

out of the water and turned in an approximately upright position to discharge its cargo, said shell being provided at one end with an opening that is closed by a cover; a 5 number of approximately ring-shaped hollow members surrounding said shell, and a number of approximately ring-shaped hollow members surrounding the members first referred to and arranged staggered relatively thereto; substantially as described.

10 5. A boat for the purpose described, comprising a tubular-shaped shell having tapered ends and adapted to be filled on land, then placed in the water and towed to its 15 destination, and thereafter lifted out of the water and turned out of its normal position to discharge its cargo, a cover closing an opening in one end of said shell, and devices connected to said cover and to the opposite 20 end of the shell to which tow lines or lifting cables can be attached; substantially as described.

25 6. A boat for the purpose described, comprising a cylindrical-shaped shell provided with approximately conical-shaped ends, and a cover that can be opened to place a cargo inside of the shell, said shell being

adapted to be filled on land, then placed in the water and towed to its destination, and thereafter lifted out of the water and turned 30 in an upright position to discharge its cargo; substantially as described.

7. A boat for the purpose described, comprising a closed cylindrical-shaped shell adapted to hold a cargo, and a plurality of 35 hollow ring-shaped members surrounding said shell; substantially as described.

8. A boat for the purpose described, comprising a cylindrical-shaped shell provided with approximately conical-shaped ends, a 40 number of hollow ring-shaped members surrounding said shell, and a number of hollow ring-shaped members surrounding the ring-shaped members first referred to and arranged staggered relatively thereto; sub- 45 substantially as described.

In testimony whereof I hereunto affix my signature in the presence of two witnesses, this fifth day of June 1908.

ALEXANDER NIEDRINGHAUS.
